WEB SUPPLY MECHANISM FOR PRINTING MACHINES

Albert J. Horton, White Plains, N. Y., assignor to
 R. Hoe & Co., Inc., New York, N. Y., a corporation of New York

Application September 15, 1936, Serial No. 100,858

15 Claims. (Cl. 242—58)

This invention relates to web supply mechanism for a printing or other machine operating upon a web drawn from a roll, and more particularly to improvements in web deflecting and timing means for the web deflecting means, for use in machines having equipment for joining a web of a replacement roll to the web of an expiring roll without stopping the machine, and while the latter web is running at normal speed into the machine. This invention especially contemplates the provision of a novel and improved timing means for controlling the operation of the web deflecting means and of novel means for actuating the web deflecting means of a high speed web joining mechanism.

One object is to provide an improved timing mechanism for a web deflecting mechanism of a web roll changing mechanism. Another object is to provide an improved web deflecting mechanism for a web supply mechanism.

Still another object is to provide in a web supply mechanism, the combination of an improved form of timing mechanism and an improved form of web deflecting mechanism.

It is also an object of this invention to provide a web roll changing mechanism of generally improved construction, whereby the device will be simple, durable and inexpensive in construction, as well as convenient, practical, serviceable and efficient in use.

With the foregoing and other objects in view, which will appear as the description proceeds, the invention resides in the combination and arrangements of parts, and in the details of construction hereinafter described and claimed, it being understood that various changes in the precise embodiment of the invention may be made within the scope of what is claimed without departing from the spirit of the invention.

In some respects, this invention is a continuation in part of my applications No. 53,315 filed December 7, 1935, and No. 56,302 filed December 27, 1935. This invention contemplates improvement over the web deflector actuating mechanism shown and broadly claimed in the former of the above applications and over the timing mechanism shown and broadly claimed in the latter thereof.

The preferred embodiments of the invention are illustrated in the accompanying drawings, wherein:

Figure 1 is a partial view in elevation of a web roll changing mechanism embodying the features of this invention;

Figure 2 is a partial view of a portion of Fig-

ure 1 showing the web deflector actuating mechanism of this invention in another position;

Figure 3 is a diagrammatic view of a somewhat modified form of associated web deflector actuating mechanism and timing control switch;

Figure 4 is an end view of one arm of a web roll carrying member showing the improved form of timing mechanism of this invention;

Figure 5 is a partial section on line 5—5 of 10 of Figure 4; and

Figure 6 is a partial view of a form of timing mechanism showing a somewhat modified form of means to permit its use with either half or full length web rolls.

The web roll changing mechanism selected to illustrate the features of this invention and shown in Figure 1, may be of the construction generally shown and described in detail in the above mentioned application No. 53,315. 15

This mechanism includes a rotatable web roll supporting reel 11 having spaced apart opposing sets of arms 12, one set of which is axially movable along a shaft 129, upon which the sets of arms are mounted, extending therefrom upon which web rolls 13, 14 and 15 may be rotatably mounted in accordance with the general practice. In this instance, web roll 13 is the expiring roll from which the web 16 thereof, is directed over guide rollers 17 into a machine adapted to 20 operate thereon, such as a printing machine. Roll 14 is the replacement roll, which is shown after the reel 11 has been rotated to position it in proper relation to the web 16 to have its web joined thereto. Roll 15 is another web roll in 25 position to be moved into the position now occupied by the roll 14 when occasion demands the same. In the web supply mechanism illustrated, provision is made for rotating the replacement roll 14 before and during the joining of its web 30 with the web 16 of the expiring roll 13. The roll rotating means is herein indicated as comprising a driven belt 18 in driving engagement with the roll 14. 35

A web deflecting and severing mechanism is 40 also shown whereby the web 16 may be deflected toward and into engagement with the roll 14 to be connected to the web thereon in accordance with the well known method of pressing the running web 16 against an adhesive covered area 45 114 on the web end of the web roll 14 at the moment this area is in proper relation with the web for such operation to be performed, and then to substantially simultaneously with such operation sever the web 16 between the web join 50 55

and the expiring roll 13. This mechanism, for the purpose of this description, may be considered as being a combination of two devices operable in cooperation to join the web 16 with the 5 web of the replacement roll 14 and is herein shown supported from a machine frame 19 by and between brackets 21, which extend downwardly from the frame, one at each end of the reel 11 and which also support the guide rollers 10 17. Both of these devices, one of which carries a web engaging and deflecting member, herein 15 in the form of a brush 22, and the other of which carries a web severing knife in a holder 23, are pivotally mounted upon a shaft 24 extending between the brackets 21, so that they 20 may be swung backward and upward out of the way as shown in dotted lines in Figure 1, when they are not in use.

The web deflecting member or brush 22 is 25 mounted upon a supporting bar 25, which extends between arms 26 pivotally mounted on the shaft 24. The web severing means including the holder 23 is supported upon and between arms 27 which are pivotally mounted upon the shaft 24 and are 30 limited in their forward pivotal movement by stop pins 28, one on each arm and disposed to engage a lug 29 depending from each of the brackets 21. The member or brush 22 and the edge of the holder 23 are permitted sufficient 35 movement to engage and firmly press against the web 16 under constant urge of springs 31, one of which is secured to each arm 27 on a stud 32, and to the adjacent bracket 21 at 33. The arms 26 are normally locked to the arms 27 40 by a releasable connection herein constituted by a releasable spring retained catch member 34 pivotally mounted at 30 to the arm 27 and a pin 35 on the arm 26 which is engaged by a hook 36 formed on one end of the catch member 34. The 45 other end of the member 34 is connected to the movable core 37 of a solenoid 38 mounted upon the arm 27. Energization of the solenoid 38 will pull the core 37 to rock the member 34 and thereby release the pin 35 from the hook 36 and permit pivotal movement of the arms 26 relatively to the arms 27, toward the replacement roll 14 to cause the brush 22 to deflect the web 16 into engagement therewith.

Herein is shown a cable 39, one end of which 50 is secured to one of the arms 26, led over a suitably disposed pulley 41 rotatably mounted upon the frame 19. The other end of the cable 39 is secured to the end of a spring 42, which is in turn secured to an arm 43 secured upon a shaft 44 journaled in a bracket 45, herein shown mounted upon an upright machine frame member 46. A 55 manually actuated lever 47, also secured to the shaft 44, extends outwardly from the bracket 45 to dispose its handle end 48 in a convenient position to be actuated by the machine operator to stretch the spring 42 to impose a constant urge, through the cable 39, upon the arms 26 and by them upon the brush 22 to pull it toward the roll 14 upon actuation of the member 34, by the 60 energizing of the solenoid 38, to release the pin 35 from the hook 36. An adjustable stop member, constituted by a screw 49 and lock nut 51 mounted on an arm 52 extending from the bracket 45, is adapted to be engaged by the lever 47 when it is 65 actuated, as shown in Figure 1, by being pulled downwardly, to limit its movement, and whereby the force applied to the brush 22 may be varied and the desired degree of pressure imposed upon the web 16 as it is pressed against the roll 14, 70 may be obtained. Movement of the lever 47 in

its actuating direction causes it to engage the actuating arm 50 of a spring released control switch 53 to engage suitable contacts thereof and close a circuit leading therethrough for a purpose to be hereinafter described. When not in use the lever 47 may be swung upwardly into the position shown in Figure 2 whereby the switch is released and the circuit controlled thereby is maintained open. If preferred, the circuit controlled by the switch 53 may be closed by a push button switch 54 instead of the switch 53 and which may be disposed remote from the lever 47, as illustrated in Figure 3.

The timing mechanism of this invention as 15 illustrated in Figures 1, 4 and 5 is an improvement over the forms shown in the above mentioned application No. 56,302 and includes a cam 55 mounted on each roll spindle 56 to rotate with the respective roll and means actuated by the cam 55 to close a spring released switch 57 20 mounted upon the hub or reel arm member 58 of the reel 11. The switch 57 is secured upon a bracket 59 which in turn is secured upon a ring 61 mounted upon rollers 62 secured to the end face of the hub 58 by screws 63. Washers 64, disposed 25 under the heads of the screws 63 are arranged to maintain the ring 61 and the roller 62 against axial movement relatively to the hub 58. A rod 65 extends from the lower side of the ring 61 downwardly and into a groove 65' formed between the spaced apart bars 70 and 70', whereby the switch 57 is maintained in proper position and against rotative movement in respect to the means to close the same, which is actuated by the cam 55. The switch 57 is provided with an actuating 30 lever 66 having a roller 67 rotatably mounted on its free end and which is adapted to be engaged by an arm 68 formed on a member 69 rotatably mounted upon a shaft 71 supported by the bracket 59. The member 69 is normally urged toward 40 the end of an adjusting screw 72 extending from a lug 73 on the bracket 59 by a spring 74 and is provided with an arm 75 upon which a roller 76 is rotatably mounted.

The roller 76 is normally disposed in the path 45 of movement of a cam plate or leaf 77 formed on the end of a rod 82, and a finger 79 is provided which extends upwardly from the leaf 77 through the rod 82 in the lug 78. The rod 82 is secured to a 50 slide 83 in which a cam follower or roller 84 is journaled. The slide 83 is slidably supported in a lug 80 formed on a member 85 secured by screws 86 to the roll spindle end of the respective roll supporting arm to position the roller 84 in operative engagement with the cam 55. The rod 82 is 55 slidably supported in lugs 87 and 78 formed on the bracket 81 which is secured to the respective roll supporting arm by screws 89. A spring 91 reacting against and disposed between the lug 87 and a collar 92 secured on the rod 82, constantly urges the rod 82 and through it the cam plate 77 60 against the roller 76 when the reel is in the position shown.

The plate 77 is provided with turned up ends 93 65 to facilitate the engagement of the same by the roller 76 when the reel 11 is rotated to position a web roll in web joining position as indicated in Figures 1 and 4. The roller 84 is maintained out of engagement with the cam 55 by the spring 91, 70 except when the roller 76 engages the plate 77. Thus, the parts are not operated by rotation of the cam unless the plate 77 is in engagement with the roller 76. The spring 74, however, is made of sufficient strength to overcome the spring 91 and 75

5 maintain the parts in the position shown in Figure 5 except when the plate 77 is forced down by the cam 55.

10 The provision of the ring 61 upon which the switch 57 is supported and which is mounted upon the hub of the reel 11 to permit relative rotation therebetween and secured thereon against relative axial movement in respect thereto, adapts the timing mechanism to be used with 15 half length rolls as well as full length rolls, the arrangement including the rod 65 and bars 70 and 70' constantly maintaining the switch in position to be engaged by the plate 77 when a replacement roll is in web joining position.

15 Figure 6 illustrates another form of means to maintain the switch 57, through its supporting ring 61, in proper operative position for its use with rolls of varying length. In Figure 6, each side of the ring 61 is pivotally secured to the end 20 of a bar 121. The other end of each of the bars 121 are pivotally connected to the ends of a pair of bars 122 by a rod 123 and nuts 124. The other ends of the bars 122 are pivotally mounted, one 25 on either end of a bracket 125, upon a rod 126, journaled in the bracket 125. The bracket 125 is secured to the reel shaft supporting bracket 99 by screws 127. A brace rod 128 extends between the bars 122 adjacent their connection with the bars 121. The bars 121 and 122 constitute an 30 extensible device whereby the ring 61 may be moved with the reel arm member 58 axially along its shaft 129, when being adjusted to support web rolls of different lengths and be retained against rotative movement relatively to the reel to maintain the switch 57 in operative position. The bars 121 and 122 are shown in extended position in full lines in Figure 6, whereby a web roll of less than full length may be supported, and in folded 35 position by dotted lines, to indicate their relative positions when a full length roll is in use.

40 Referring to Figure 1, one terminal 101 of the switch 53 is shown connected by a conductor 102 to the line wire L1 and the other terminal 103 is shown connected to one terminal 104 of the 45 solenoid 38 which actuates the catch 34 by a conductor 105. The other terminal 106 of the solenoid 38 is shown connected to one terminal 107 of the switch 57 by a conductor 108 and the other terminal 109 of the switch 57 is shown connected to the line wire L2 by a conductor 111. In the arrangement shown in Figure 3, the switch 53 is omitted and replaced by the remotely positioned 50 push button switch 54, to the terminals 112 and 113 of which conductors 102 and 105 are respectively connected. The preferred circuit arrangement shown in Figure 1 is such that when the arms 26 and 27 are brought down into web prejoining position as shown in Figure 1, and the lever 47 is actuated, to simultaneously engage the 55 stop 49, to impose a tension on the spring 42, and to close the control switch 53, the solenoid 38 will be energized to actuate the catch member 34 and release the arm 26, to permit the brush 22 to deflect the web 16 and press it against the roll 14, when the switch 57 is closed by action of the cam 55 through the rod 82, plate 77, roller 76, and the 60 arm 68, upon the switch actuating lever 66. The web end on the roll 14 is arranged in such relation to the cam 55 that the cam will actuate the switch 57 preferably when the edge of the adhesive covered area 114 is at the top of the roll, thus allowing ample time for the brush 22 to swing and press the web 16 into contact with the roll 14, by the time the pasted area 114 passes 65 under the brush, and the web splice is made.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a web roll changing mechanism, a movable web deflecting member, means to restrain said member, electrically operable means to release said restraining means, a switch in circuit 15 with said electrically operable means, a manually operable member for simultaneously exerting a pull on said web deflecting member and actuating said switch, and resilient means connecting said manually operable means and said web deflecting 20 member.

2. In a web roll changing mechanism, a movable web deflecting member, means to restrain said member, electrically operable means to release said restraining means, a switch in circuit 25 with said electrically operable means, a manually operable member for simultaneously exerting a pull on said web deflecting member and actuating said switch, adjustable means to limit the movement of said manually operable member, 30 and resilient means connecting the manually operable means and the web deflecting means.

3. In a web roll changing mechanism, a movable web deflecting member, means to restrain said member, electrically operable means to release 35 said restraining means, a switch in circuit with said electrically operable means, a manually operable member for simultaneously exerting a pull on said web deflecting member and actuating said switch, means to connect said manually 40 operable means and said web deflecting member including a spring member adapted to bias the web deflecting member toward the web, and means to vary the effective tension on said spring member.

4. In a web roll changing mechanism, a movable web deflecting member, means to restrain said member, electrically operable means to release 50 said restraining means, a switch in circuit with said electrically operable means, a manually operable member for simultaneously exerting a pull on said web deflecting member and actuating said switch, means to connect said manually operable member and said web deflecting member including a spring member adapted to bias the web 55 deflecting member toward the web, and adjustable means to limit the movement of said manually operable member whereby the effective tension on said spring member may be varied.

5. In a web roll changing mechanism, a movable web deflecting member, means to retain said member out of web deflecting position, controllable means operable only at certain intervals to release said member, manually operable means to exert a pull on said member and to control the 60 actuation of said controllable means, including a spring connecting said member and the manually operable means, a stop to limit the movement of said manually operable means, and a timed control means operable to permit the actuation 65 of said controllable means by said manually operable means only at certain intervals.

6. In a web roll changing mechanism, a movable web deflecting member, means to retain said member out of web deflecting position, means 70

10

45

50

55

60

65

70

75

to release the member, timed means to control the operation of said releasing means only at certain intervals, a manually operable lever, a spring to connect the member to the lever, a stop to limit the movement of the lever in member moving direction, and means cooperating with said timed means and actuated by the lever when the same is moved against the stop to control the controlling action of said timing means upon 10 said releasing means.

7. In a web roll changing mechanism, a movable web deflecting member, a catch member to retain the member out of web deflecting position, a solenoid to release the catch, a manually operable lever, a spring connecting the lever to the member, a stop to limit the movement of the lever, and a switch in circuit with the solenoid and adapted to be actuated by movement of the lever toward the stop.

20 8. In a web supply mechanism, a rotatable web roll supporting reel, a movable web deflecting part, a catch to retain said part out of web deflecting position, a solenoid to release the catch, a member mounted on said reel, a first switch mounted 25 on the member for controlling a circuit to actuate the solenoid, means to prevent rotation of the member with said reel, a spring connected to the web deflecting part, a manually operable lever connected to the spring and operable to tension it 30 and impose a pull upon said part, and a second switch for controlling the circuit of said first switch and adapted to be actuated by the lever when the same is operated to increase the tension on the spring.

35 9. In a web supply mechanism, a movable web deflecting part, means to retain the part out of web deflecting position, electrical means to release said retaining means, a spring connected to the web deflecting part, a manually operable lever for 40 tensioning the spring to cause it to impose a pull upon said part, and an electrical switch in the circuit of said electrical releasing means adapted to be actuated by the lever when the same is operated to tension the spring.

45 10. In a web supply mechanism, a movable web deflecting part, means to retain the part out of web deflecting position, electrical means to release said retaining means, a spring connected to the web deflecting part, a manually operable lever 50 for tensioning the spring to cause it to impose a pull upon said part, an electrical switch in the circuit of said electrical releasing means adapted to be actuated by the lever when the same is operated to tension the spring, and an adjustable 55 stop for varying the spring tensioning action of said lever.

11. In a web supply mechanism, a movable web deflecting part, means to retain said part out of web deflecting position, means to release said retaining means, a rotatable axially movable web roll supporting member, a control support mounted on said member and carried thereby during axial movements thereof, a control for said releasing means mounted on said support, a stationary support for said member, and a pair of bars pivoted to each other at adjacent ends, the other end 10 of one bar being pivotally secured to said control support and the other end of the other bar being pivotally secured to the stationary support.

12. In a web supply mechanism, an axially movable web roll supporting member, a stationary support for said member, said member being mounted for rotative movement relatively to said support, a mechanism control support adapted to be carried by said member during its axial movement, and extensible means connecting said 20 control support with said stationary support to hold the control support substantially stationary in respect to any rotative movement of said member.

13. In a web supply mechanism, in combination, an axially movable web roll supporting member, a stationary support for said member, said member being mounted for rotative movement relatively to said support, a web deflector, means to hold said deflector out of web deflecting position, electrical means to release said deflector holding means, an electrical switch in the circuit of said electrical releasing means and connected to said web roll supporting member to be axially moved therewith, and extensible means connected 30 to said stationary support and adapted to hold said electrical switch stationary in respect to any rotative movement of said member.

14. In a web supply mechanism, an axially movable web roll supporting member, said member being mounted for rotative movement, a mechanism control carried by said member and axially movable therewith, and extensible means adapted to retain said control stationary with respect to any 40 rotative movement of said member.

15. In a web supply mechanism, a movable web deflecting member, electrically controlled means to releasably hold the web deflecting member, a manually swingable lever, a connection between said member and said lever including a spring 50 whereby swinging of said lever will impose a spring urge upon said member to move it, an electrical switch positioned to be actuated by said lever when it is swung, and electrical connections between said electrically controlled means and said switch. 55

ALBERT J. HORTON.
